UNITED STATES PATENT OFFICE.

JOSEPH MATTE, JR., OF DETROIT, MICHIGAN.

ANCHOR.

Application filed October 15, 1926. Serial No. 141,686.

My invention relates to anchors for mounting laterally extending bars and particularly to a type of anchor for horizontally disposed angle bars for supporting the brick or stone 5 work forming the outer facing of the wall of a steel or concrete building. In buildings of this type, the angle bars for the facing are usually attached in position by two workmen, and it is important that the arrangement be 10 such that the two men in cooperation can readily and easily apply and tighten the bars in approximately their final adjusted position. It is likewise important that the bars be capable of ready adjustment later by one 15 workman or by two workmen at the most to their final adjusted position for supporting the courses of stone or brick to be carried thereby in accurately adjusted position with respect to the other courses adjacent thereto. 20 It is also important that the hangers be of such an arrangement that they can be tightened properly without danger of breakage and that the hangers when tightened shall have a substantially positive gripping effect 25 on the angle bars of such strength as to be effective without material danger of failure.

It is the object of my invention to provide a construction of this type having the several desirable features above outlined, so that 30 the angle bars can be placed quickly and easily in the desired adjusted position and that the facing portions of the wall shall be securely and safely supported thereon. It is another object of my invention to improve devices of 35 this type in sundry details hereinafter pointed out. The preferred means by which I have accomplished my several objects are illustrated in the drawing and are hereinafter specifically described. What I desire to cover by 40 Letters Patent is set forth in the claims.

In the drawing,—

Fig. 1 is a face view showing fragmentary portions of an angle bar supported in position on the face of a concrete wall ready for 45 the application of brick or stone work thereto.

Fig. 2 is a vertical cross section taken substantially at line 2—2 of Fig. 1, and showing in dotted lines the forms between which the wall was molded.

Fig. 3 is a vertical cross section through my improved insert box of the type preferably used in connection with a concrete wall structure, and showing in dotted lines a changed position of the securing bolt.

Fig. 4 is a face view of the box of Fig. 3.

Fig. 5 is a view similar to a portion of Fig.

3, but showing a modified form of construction.

Fig. 6 is a face view of a modified form of insert box.

Fig. 7 is a vertical cross section through an I-beam forming a part of the framework of a steel building and having my improved anchor device mounted thereon; and

Fig. 8 is a view similar to Fig. 7 but showing a modified arrangement and including a box for protecting the bolt and its associated parts from the concrete to be placed about the steel.

Referring now particularly to Figs. 1 to 4 inclusive, 15 indicates a concrete wall having been molded between forms 16 of any suitable type and provided at intervals therealong with insert boxes 17 embodied in the wall for adjustably holding in position securing bolts 18 by which an angle bar 19 is adjustably secured in position for supporting the facing portion of the wall. As is well understood in the art, it is difficult to place the boxes 17 accurately in position so that a plurality of the 80 boxes may be in perfect alignment in the finished and hardened wall, wherefore it is necessary or important that the boxes be provided with adjustable means for supporting the bolts 18 so that the bolts may be placed in the 85 desired alignment regardless of the slight discrepancies in the position of the boxes. It is also important that the entire set of bolts 18 for one of the angle bars 19 be adjustable similarly up and down so that the bar 19 can be 90 placed accurately in position with respect to the facing portion of the wall below regardless of slight variations in the position of such facing portions so that the bar 19 can support the next higher course of stone or brick 95 in the desired relationship to the courses below. The vertical adjustment of the bolts 18 with respect to the boxes is effected in the manner hereinafter described, while the horizontal adjustment is secured by the provision of horizontally disposed slots 20 for the bolts 18 in the vertically extending portion of the bar 19.

The insert boxes 17 in the embodiment shown in Figs. 1 to 4 are in the form of castings comprising side walls 21, a top wall 22 and a bottom wall 23, with a back wall 24 formed integrally with the other walls and comprising an outwardly extending flange 25 about the entire periphery of the box. In 110 the construction shown, the side walls 21 converge downwardly with respect to each other

so as to provide a vertical support for the box within the concrete wall even though the bottom face of the box is flush with the bottom edge face of the wall, as is sometimes the case. By the provision of the flange 25, the box is secured very strongly in position with respect to a forward pull upon the box by which the box might otherwise be drawn forwardly out of position within the wall.

10 In the construction shown, the front wall portion of the box is in the form of a wedge indicated by the numeral 26, having its front and rear faces diverging slightly downwardly, the front face of the wedge member being 15 adapted to conform to the vertical position of the rear face of the bar 19 while the rear face of the wedge member diverges downwardly to a slight degree with respect to the rear face of the bar 19. The side edges of the 20 wedge member 26 merge with the side walls 21 of the box throughout the full thickness of the wedge so as to provide the desired support for the wedge member with respect to the box.

25 In forming the wall 15, a plurality of the boxes 17 are secured in position upon the form 16 with the front faces of the boxes in contact with the form, the boxes being very firmly secured in position upon the form 30 by the use of heavy nails 27 extending through openings 27^a through the box, such nails being preferably clinched upon the outer face of the form 16. For assisting the workman in placing the boxes in proper 35 position, I have provided markers 27^b in the form of ribs extending across the top face and the side faces of the box.

The bolts 18 are inserted into position in the boxes 17 through T-slots 28 in the wedges 40 26, such slots extending the full depth of the box from the top wall 22 to the bottom wall 23, as is best shown in Fig. 3, the arrangement being such that the head portions of the bolts can be entered through 45 the enlarged portions of the T-slots after the boxes are in position. In the form shown in Figs. 1 to 4, the bolts 18 are standard bolts having square heads, being provided with auxiliary head members 29 in the form 50 of heavy washers. In the construction here shown, the head members 29 are cut away at opposite sides so as to provide lugs 30 at opposite sides of the bolt for engagement in the slots 28 for holding the washers against 55 rotation, the washers being cut diagonally so as to provide extended bearing faces for the bolts at an angle conforming to the inclination of the rear faces of the wedge members 26. The washers 29 are provided in the construction 60 shown with lugs 31 engaging the heads of the bolts 18 for holding the bolts against rotation with respect thereto.

When it is desired to apply an angle bar 19 in position, two workmen handle the opposite 65 ends of the bar for inserting the bolts of the

end boxes 17 through the slots 20 at the ends of the bar, the nuts on the bolts 18 being screwed up sufficiently for holding the bar loosely in position. The bolts 18 of the intermediate boxes 17 are then inserted through 70 the corresponding intermediate slots 20 of the bar 19 and the nuts are threaded upon their outer ends. For enabling the intermediate bolts 18 to be inserted readily through their slots 20, it is important that the bolts be capable of retraction almost completely into the boxes, as shown by the dotted line position of the bolt in Fig. 3, the box 17 being formed of a size to enable such manipulation of the parts. When the bar 19 is to be tightened 80 into position, the ends of the bar are placed at the desired height and the nuts on the end bolts are tightened into position. As will be readily seen, when it is desired to adjust the bar 19 vertically after all of the bolts 18 are 85 in position through the slots 20, this can be accomplished readily by vertical movement of the ends of the bar in unison or by an adjustment of either end of the bar by itself, the intermediate bolts 18 being adapted to 90 move without resistance either upwardly or downwardly along the slots 28 of the intermediate boxes. When the bar has been tightened into position at its ends, the intermediate bolts 18 are also tightened, and all of 95 the bolts, so far as is necessary or advisable, are cut off so as not to interfere with the courses of brick or stone.

As will be readily understood, when one of the bolts 18 is tightened in position by the nut on the outer face of the bar 19, the bar is held positively against downward movement, inasmuch as such downward movement would necessitate a greater length of bolt. The inclination of the rear face of the wedge member 26 is so slight that at the same time the bar 19 is held very strongly by friction against upward movement with respect to the wedge member 26, the frictional engagement between the head portion of the bolt and the rear face of the wedge being very great by reason of the fact that the head portion is beveled to correspond with the angle of the wedge. By reason of the very slight taper of the wedge member 26, the distance 105 between the rear face of the wedge at the bottom of the box and the front face of the bar 19 is kept within practical limits so that the support for the bolt 18 shall be kept adequate even when the bolt is adjusted to its lowermost 110 position in the slot 28.

In Fig. 5, I have shown a modified form comprising a bolt 32 having its head 33 cut away at the sides to conform to the slant of the wedge 26 and for holding the bolt against 115 rotation with respect to the wedge without the use of an auxiliary head member or washer 29. In cases where a bolt of the type shown in Fig. 5 can be obtained to advantage, this construction is to be preferred to the con- 120 125 130

struction illustrated in Fig. 3. The operation of the two devices is substantially the same.

In Fig. 6 I have shown a modified form of insert box in which the side walls 34 parallel 5 instead of being convergent downwardly as in Fig. 4. To compensate for this change so as to provide the desired vertical support, I have provided laterally projecting ribs 35 extending across the side walls 34 in spaced 10 relation to the lower end of the box, in the construction shown the ribs 35 being placed at the top of the box. Inasmuch as the construction is otherwise substantially in accordance with that above described, it is believed 15 to be unnecessary to describe the same herein, the operation being substantially as above described.

In Fig. 7 I have shown my improved anchoring means applied directly to the fabricated steel frame of a building. In this construction, an angle 36 is riveted to the web of an I-beam 37 of the framework, with a second angle 38 riveted thereto. The angle 38 is provided with a vertically disposed slot 39 cor- 20 responding to the slot 28 of the construction shown in Fig. 4. A wedge member 40, preferably in the form of a casting or a stamping and having its rear face diverging downwardly with respect to its front face which 25 is defined by the edges of the flange portions, is secured by means of a rivet or other form of bolt 41 upon the angle 38, the wedge member 40 being provided with a slot 42 corre- 30 sponding in shape, size and position with the slot 39. A plurality of such supporting parts are provided along the I-beam 37 or along other parts in the desired alignment for sup- 35 porting an angle bar 43 by means of bolts 44, the bolts 44 in the construction illustrated in Fig. 7 corresponding with the bolts 32 of Fig. 5 rather than with the construction shown in Fig. 3. Inasmuch as the operation of the parts here described corresponds exactly with that above described in connection with Figs. 40 1 to 4, it is believed to be unnecessary to de- 45 scribe it further.

In Fig. 8, the construction is the same as that shown in Fig. 7, except that the slot 45 is formed directly in the web of the beam 46 50 of the frame work of the building, the beam 46 being shown as a channel beam rather than an I-beam. In the construction shown in Fig. 8, the angle bar 47 is also shown with its out- 55 wardly extending flange at the top rather than at the bottom as in the remaining figures. The bolt 44 and wedge member 40 are also 60 enclosed at the rear face of the beam 46 by means of a sheet metal casing 48 preferably secured in position by welding for protecting the parts from the concrete by which the rear 65 face of the beam is to be inclosed.

While I prefer to employ the construction as illustrated in my drawing and as above described, it will be understood that I do not 65 wish to limit my invention to the use of the

features there illustrated except as the claims are hereinafter specifically so limited, since it will be understood that changes may well be made in the construction without departing from the spirit of my invention.

70

I claim:

1. In anchoring means for a laterally ex- 75 tendsing bar, the combination of a slotted wedge member extending across the bar with its rear face diverging downwardly from the rear face of the bar, a bolt extending through the slot in said wedge member and through an opening in the bar and having head means beveled to correspond with the diagonally disposed face of the wedge, and means cooperat- 80 ing with said bolt for holding said bar rigidly in position with respect to said wedge member.

2. In anchoring means for a laterally ex- 85 tendsing bar, the combination of a slotted wedge member extending across the bar with its rear face diverging downwardly from the rear face of the bar, a bolt extending through the slot in said wedge member and through an opening in the bar and having head means comprising a part removably mounted on the shank of the bolt having a face beveled to correspond with the diagonally disposed face of the wedge and serving by engagement with the wedge member to hold the bolt from rotation, and means cooperating with said bolt 90 for holding said bar rigidly in position with respect to said wedge member.

3. In anchoring means for a laterally ex- 95 tendsing bar, the combination of a slotted wedge member extending across the bar with 100 its rear face diverging downwardly from the rear face of the bar, a bolt extending through the slot in said wedge member and through an opening in the bar, a washer non-rotatably mounted on said bolt serving to hold the bolt 105 from turning with respect to the wedge member, and means cooperating with said bolt for holding said bar rigidly in position with respect to said wedge member.

4. In anchoring means for a laterally ex- 110 tendsing bar, the combination of a slotted wedge member extending across the bar with its rear face diverging downwardly from the rear face of the bar, a bolt extending through the slot in said wedge member and through an 115 opening in the bar, a washer non-rotatably mounted on said bolt serving to hold the bolt from turning with respect to the wedge member and having a bearing face beveled to correspond to the angle of the rear face of the 120 wedge member, and means cooperating with the bolt for holding said bar rigidly in position with respect to the wedge member.

5. In anchoring means for a laterally ex- 125 tendsing bar, the combination of a slotted wedge member extending across the bar with its rear face diverging downwardly from the rear face of the bar, a bolt extending through the slot in said wedge member and through an opening in the bar and having head means 130

- cut away at both sides to provide a lug for engagement with the slot for holding the bolt against rotation and having the face portions at opposite sides of the lug diagonally disposed to correspond to the angle of the rear face of the wedge member, and means cooperating with the bolt for holding said bar rigidly in position with respect to the wedge member.
10. 6. In anchoring means for a laterally extending bar, the combination of a slotted wedge member extending across the bar with its rear face diverging downwardly from the rear face of the bar, a bolt extending through the slot in said wedge member and through an opening in the bar, a washer mounted on said bolt and cut away at both sides to provide a lug for engagement with the slot for holding the bolt against rotation and having face portions at opposite sides of the lug diagonally disposed to correspond to the angle of the rear face of the wedge member, a lug on the washer adapted by engagement with the head of the bolt to hold the bolt from rotation, and means cooperating with the bolt for holding said bar rigidly in position with respect to the wedge member.
7. In anchoring means for a laterally extending bar, the combination of an insert box for a concrete wall having means adapted by engagement with the wall to prevent removal of the box therefrom by a forward pull on the box and having a solid wedge member extending across the box with its front face vertical and its rear face diverging from the front face, a bolt extending through a vertically disposed slot in said wedge member and through an opening in the bar and having head means beveled to correspond with the taper of the wedge, and means cooperating with said bolt for holding said bar rigidly in position with respect to said wedge member, the rear wall of the box being in such spaced relation with respect to the wedge member that the bolt can be backed up almost but not quite entirely into the box whereby in the installation of the bar by the use of a plurality of boxes the bar can be secured by the bolts of the end boxes and the bolts of the intermediate boxes can be retracted later sufficiently for insertion into their respective openings in the bar.
8. An anchoring means for a laterally extending bar, comprising in combination a member having a vertical slot therein and having its rear face diverging downwardly with respect to its front face, a pin, head means carried by the pin adapted by engagement with the rear face of said member at opposite sides of the slot when tightened against said member to align said pin at a definite predetermined angle with respect to the front face of said member, and means for tightening said head means against said member.
9. An anchoring means for a laterally extending bar, comprising in combination a member having a vertical slot therein and having its rear face diverging downwardly with respect to its front face, a pin, head means carried by the pin adapted by engagement with the rear face of said member both above and below the pin and also at opposite sides of the slot when tightened against said member to align the pin at a predetermined angle with respect to the front face of the member, and means for tightening said head means against said member in any adjusted position vertically along said slot.
10. An anchoring means for a laterally extending bar, comprising in combination a member having a vertical slot therein and having its rear face diverging downwardly with respect to its front face, a pin, head means carried by the pin adapted by engagement with the rear face of said member at opposite sides of the slot when tightened against said member to align said pin at a definite predetermined angle with respect to the front face of said member and also adapted by engagement with the slot to hold the pin against rotation, and means for tightening said head means against said member.
11. An anchoring means for a laterally extending bar, comprising in combination a member having a vertical slot therein and having its rear face diverging downwardly with respect to its front face, a pin, head means carried by the pin adapted by engagement with the rear face of said member at opposite sides of the slot when tightened against said member to align said pin at a definite predetermined angle with respect to the front face of said member, and means for tightening said head means against said member, the divergence of the rear face of the member from the vertical being small whereby the distance between the bearing points of the pin on the bar and on the rear face of the member is very little greater when the pin is at the lower end of the slot than when the pin is at the upper end of the slot, and whereby the pin when tightened in position is held strongly by friction against upward movement with respect to the member.
12. An anchoring means for a laterally extending bar, comprising in combination an insert box in the form of a casting having a lateral flange extending about at least a portion of the box in rear of its front face adapted by engagement with the concrete of the wall in which it is imbedded to resist removal of the box from the wall by a forward pull on the box, said box having a vertical slot in its front face, a pin having head means adapted by engagement with the rear face of the slotted portion of the box when tightened thereagainst to hold the pin against downward movement along the slot,

and means for tightening said head means in operative position against said rear face of the slotted portion.

13. An anchoring means for a laterally extending bar, comprising in combination an insert box in the form of a casting having its side walls converging downwardly for operative supporting engagement with the concrete at opposite sides of the box in the wall in which it is imbedded, said box having

a vertical slot in its front face, a pin having head means adapted by engagement with the rear face of the slotted portion of the box when tightened thereagainst to hold the pin against downward movement along the slot, and means for tightening said head means in operative position against said rear face of the slotted portion. 15

JOSEPH MATTE, JR.
